HENRY LUSSIER, OF SALEM, MASSACHUSETTS, ASSIGNOR, BY MESNE ASSIGNMENTS, TO DRAPER CORPORATION, OF HOPEDALE, MASSACHUSETTS, A CORPORATION OF MAINE.

SHUTTLE.

1,226,615.

Specification of Letters Patent. Patented May 15, 1917.

Application filed February 5, 1916. Serial No. 73,233.

To all whom it may concern:

Be it known that I, HENRY LUSSIER, a citizen of the United States, residing at Salem, county of Essex, and State of Massachusetts, have invented an Improvement in Shuttles, of which the following description, in connection with the accompanying drawings, is a specification, like letters on the drawings representing like parts.

10 The invention to be hereinafter described relates to loom shuttles, and more particularly to loom shuttles employed in looms of the filling replenishing type.

In filling replenishing looms where the 15 filling carrier or bobbin is ejected from the shuttle and another carrier or bobbin with a fresh supply of filling is substituted in effecting replenishment during the operation of the loom, provision is usually made 20 for "threading" the new filling, that is leading it to and through the delivery eye of the shuttle, as the latter is picked. To secure this result, the shuttle is provided with a threading device, which on the first pick of the 25 shuttle after a replenishing operation, engages the filling and leads it to a position from which it may be drawn into the delivery eye on the return or second pick of the shuttle. Those devices have been variously 30 formed and are generally known as "threading blocks" and the shuttles themselves are usually designated "self-threading shuttles."

The threading blocks of such shuttles 35 usually have a longitudinal thread passage and a projection or beak, so formed that when the shuttle makes its first pick after replenishment, and the filling is drawn from the filling carrier by reason of the filling 40 end being fastened to a fixed part, the filling ordinarily passes into the thread passage and beneath the beak, and the preliminary step in the threading operation is accomplished. On the return or next pick of the 45 shuttle in the opposite direction, the filling is ordinarily guided into the delivery eye of the shuttle, and the threading operation is completed.

It happens at times that the filling fails to 50 find its way under the beak of the threading block on the first pick of the shuttle after replenishment, so that on the return or next pick of the shuttle the filling will lead backward to the cloth selvage directly from the 55 end of the bobbin in which position, as well

understood by those skilled in the art, the filling cannot unwind from the bobbin as the shuttle makes its return or second pick, and the filling is consequently broken. This mishap is technically known in the art as a "real mis-thread."

An important feature of the present invention consists of means for preventing "real mistreads" by providing the threading block with leaders, one, at least, of 60 which is so related to the thread passage that should the filling fail to be preliminarily threaded on the first pick of the shuttle after replenishment, that it will engage the filling on the return or second pick 65 of the shuttle and cause it to be drawn forward from the end of the bobbin as the shuttle passes through the shed. Another important feature of the invention consists in projecting a leader from one wall portion 70 of the thread passage to underlie an overhanging portion of the opposite wall, so that should the filling not be caught and preliminarily threaded by the beak, the bight 75 of filling formed as the shuttle makes its return or second pick will be prevented from moving longitudinally back from out of the thread passage toward the bobbin but will be engaged by such leader about which it will be drawn longitudinally from the bobbin 80 as the shuttle passes through the shed on its second pick.

The above and other features of the invention will be hereinafter described and then definitely set forth in the claims. 85

In the drawings:

Figure 1 is a plan view of a shuttle provided with one form of the present invention, part thereof being broken away;

Fig. 2 is a perspective view of the eye end 90 of the shuttle, showing the threading block and the filling engaged by a leader;

Fig. 3 is a detached view of the threading block having a portion of one wall broken away; and

Fig. 4 is an end view of the threading block looking from the left, Fig. 1.

The shuttle body 1 is provided with the usual chamber 2 open at the top and bottom for the reception of a filling carrier or bobbin 3 having a supply of filling 4 thereon. The filling carrier or bobbin 3 may be conveniently supported in the shuttle by any appropriate means and is herein shown as provided with a series of bobbin-holding 105 110

rings 5 adapted to engage the bobbin-holding jaws 6 secured to the shuttle. These parts may be of usual and well understood construction.

5 The eye end of the shuttle is provided with a cavity formed in the shuttle wood, as at 7, for the reception of a threading block, and has a delivery eye 8 shown as extending through the side wall of the shuttle and through which the filling from the bobbin usually passes during the passage of the shuttle through the shed.

10 The threading block is provided with a base portion 9 having upwardly-extending side walls 10 and 11 through which extends the longitudinal thread passage 12. In the illustrated form of the invention the thread passage 12 is of generally circular form in cross section as illustrated in Figs. 3 and 4, 15 and has a contracted passage 13 leading thereto. Above the contracted passage 13 is a vestibule or longitudinal opening 14 into which the thread may be first delivered as the shuttle makes its first pick after replenishment. While these details of construction 20 have been found in practice to be a good, practical form of the longitudinal thread passage, it is to be understood that the invention is not restricted thereto, but 25 such thread passage may be otherwise formed, the essential in this respect being that the threading block be provided at its lower portion extending longitudinally thereof with a suitable passageway for the 30 filling leading from the filling carrier or bobbin in the shuttle. The top portion 15 of the side wall 10 of the threading block is substantially of triangular form and downwardly curved to the contour of the top and 35 side portions of the shuttle wood, substantially as indicated in Figs. 1 and 2, the construction being such that this portion of the threading block shall find a proper seat in the cavity of the shuttle wood and offer 40 a continuous unobstructed surface over which the filling may readily pass. The forward top portion of the part 15 of the threading block has a lateral projection which forms a beak 16, the top surface portion 45 of the beak at 17 being curved to direct the thread lying on the beak downwardly into the thread passage.

50 The opposite side wall portion 11 of the threading block is extended forwardly as 55 indicated in Figs. 1 and 2, to form a guard 18 overhanging the beak 16, the construction being such that should the thread be laid longitudinally of the threading block as the shuttle makes its first pick after replenishment, it will be guided by the top 60 surface of the guard 18 and forwardly-extending portion of the surface 15 downwardly onto the beak 16 and then be by the beak directed to a position thereunder so 65 that the filling on the first pick of the shut-

tle, will be preliminarily threaded. The guard 18 may be conveniently provided with a diagonal directing edge portion 19 to facilitate the preliminary threading operation of the filling.

70 Extending downwardly from the base portion of the beak 16 is a guiding surface 20, usually denominated a "horn" the construction being such that after the shuttle has been preliminarily threaded on the first pick of the shuttle after replenishment, that is, has been positioned in the thread passage and below the beak, it will, on the return or next pick of the shuttle, be guided by the horn downwardly and between the forward edge of the surface 15 of the threading block, and the wood of the shuttle, into the thread eye 8, from which it will be delivered during the weaving operation. The parts thus far described may be varied in 75 form, suited to the intended purpose. In the present instance, the parts thus far described may be substantially the same as the similar parts in the Northrop Patent No. 769,914, dated September 13, 1904.

80 It will happen at times after a replenishing operation, that the filling leading from the filling carrier in the shuttle will fail to be preliminarily threaded, or pass below the guard 18 and the beak 16 when the shuttle makes its first pick, so that on the return or second pick of the shuttle, instead of being guided by the horn 20 downwardly into the delivery eye 8, the filling will leave the thread passage and draw directly back from the end of the bobbin in the shuttle, with the result that the filling will be broken as the shuttle returns or makes its second pick. Various causes may contribute to this defective action in the 85 threading operation, such as lint accumulation, the air currents incident to the weaving operation, etc., but usually the cause for such real-mistread is temporary, and if breakage of the filling can be prevented on 90 the return or second pick of the shuttle, it will, under ordinary conditions, be preliminarily threaded or find its way below the beak 16 on the third pick of the shuttle and then on the fourth pick be directed to the 95 delivery eye.

100 The present invention, therefore, contemplates the provision of fixed leaders so associated with the opposed portions of the threading block that should the filling fail 105 to be preliminarily threaded on the first pick after replenishment, it will be engaged by one of the leaders on the second or return pick of the shuttle, and continue to be drawn longitudinally from the end of the 110 filling carrier or bobbin in the shuttle when the shuttle makes its second or return pick.

115 Above the longitudinal thread passage in the threading block is a thread entrance 21 through which the filling may pass to the 120

125

longitudinal thread passage as the shuttle makes its first pick after replenishment, and extending transversely above the longitudinal thread passage is a leader 22 formed as a shouldered portion, substantially as indicated in the Northrop patent hereinbefore mentioned.

Back of the leader 22, that is, in position between the leader 22 and the end of the bobbin, is another leader 23 which, for identification herein, may be designated the rear leader, with reference to the leader 22. The leader 23 is preferably formed in the top portion 15 of the side wall 10 by slotting such side wall as at 24, and the end portion 25 of the rear leader extends transversely of the thread entrance to underlie an overhanging portion 26 of the opposite wall 11 of the threading block, the construction being such that should the filling fail to be preliminarily threaded on the first pick of the shuttle after replenishment, and on the return or second pick of the shuttle the bight of filling fail to be engaged by the front leader 22, it will unerringly be engaged by the rear leader 23 because the end 25 of said leader extends across the thread entrance as indicated in Fig. 1, and closes the entrance of the thread passage to movement of the bight of filling past the leader 23 and the parts take position substantially as indicated in Fig. 2.

As will be noted from viewing Figs. 3 and 4, the top surface of the part 15 of the threading block is inclined downwardly toward the thread passage and so, also, is the top 27 of the opposite wall, but in the present instance of the invention the end 25 of the rear leader extends beneath the inner edge portion of the opposite wall sufficiently to insure that the filling cannot be drawn backward toward the bobbin without positive engagement by the rear leader 23 which thereupon takes control of the filling and causes it in the subsequent movement of the shuttle, to be drawn longitudinally from the end of the filling carrier or bobbin contained therein, thus avoiding a real-misthread or breakage of the filling on the return or second pick of the shuttle after a replenishing operation.

It may not be necessary in all cases to employ the front leader 22, because the rear leader 23 effectively acts to prevent a real-misthread, and in many cases it alone is sufficient for this purpose.

The threading block is provided at its lower portion with the stud 28 which may engage an appropriate recess in the shuttle

wood, and in connection with a retaining bolt 29 passed through an opening 30 of the threading block, serves to effectively hold the threading block in operative position.

What is claimed is:

1. A loom shuttle adapted to contain a supply of filling and having a delivery eye, a threading block having a longitudinal thread passage and an entrance thereto, a front leader and a rear leader extending from a side wall of the threading block over the thread passage and disposed at different points longitudinally of the thread passage, and a guard overlying the end of one of said leaders to prevent a bight of filling being drawn past the underlying leader on the second pick of the shuttle when the latter has failed to be preliminarily threaded after replenishment. 65

2. A shuttle provided with a threading block having a longitudinal thread passage, two leaders extending from one side wall of the threading block above the thread passage and at different distances from the end of the shuttle, one of said leaders extending farther from the side wall than the other. 80

3. A shuttle provided with a threading block having a longitudinal thread passage, a front leader extending from one side wall of the block above the thread passage to engage the filling should the shuttle fail to be threaded on the second pick following replenishment, and a rear leader extending from a side wall to a greater distance than the other leader to catch the filling when it fails to be held by the front leader. 90

4. A shuttle provided with a threading block having a longitudinal thread passage, a front leader extending from one side wall of the block above the thread passage to catch the filling when it fails to be threaded on the second pick following replenishment, a rear leader extending from a side wall to a greater distance than the other leader, 100 and a guard overhanging the end of the rear leader to catch the filling when it fails to be held by the front leader. 105

5. A shuttle having a threading block provided with a longitudinal thread passage, and a horn having a beak, a rear leader extending from one side wall of the threading block; a guard overhanging said leader, and a front leader between the rear leader and beak. 110

In testimony whereof I have signed my name.

HENRY LUSSIER.
